UNITED STATES PATENT OFFICE.

ANDREW L. HENRY AND GILES S. MOORE, OF INDIANAPOLIS, INDIANA, ASSIGNEES TO
TROLLEY SHOE WHEEL COMPANY, OF INDIANAPOLIS, INDIANA, A CORPORATION
OF INDIANA.

TROLLEY.

Application filed November 7, 1924. Serial No. 748,484.

Our said invention relates to a trolley and it is an object of the same to provide a device of this character with a shoe taking the place of the usual wheel, said shoe being mounted to float on a pivot on the trolley-pole, and being so formed that it will maintain the same balanced relation on the pole at all times regardless of the extent of abrasion of the shoe by the friction of the wire.

Another object is to provide means for indicating the limit of permissible wear so that employees of a trolley company will have immediate and certain information as to when the shoe should be removed and discarded. In cases where the shoe is an integral part of the trolley this will mean of course that the entire trolley is to be discarded at this time, but where a removable wear shoe is used it will be necessary only to replace the wear shoe.

Still another object is to improve the means for conducting current from the wire through the trolley.

A further object of the invention is to provide improved means for limiting the swing of the trolley when the trolley is off the wire from any cause.

Referring to the accompanying drawings, which are made a part hereof and on which similar reference characters indicate similar parts,

Figure 1 is a side elevation of our device in one position of use,

Figure 2, a side elevation in another position,

Figure 3, an end elevation of the trolley, and

Figure 4, a section on line 4—4 of Figure 1.

In the drawings reference character 10 indicates a harp having forks 11. Such harp may be of ordinary conventional character or of any desirable construction adapted to cooperate with the features of our improved trolley. A pin 12 passes through bearings at the upper end of the trolley harp and is secured in place in any convenient manner this pin providing a bearing for the trolley,

which has side flanges 13 forming a groove 50 between them. In the position shown in Figure 1 the groove provides a shoe having a straight face at 14 which face is horizontal in Figure 1, i. e. during forward movement of the trolley.

In the operation of trolley shoes it is important that the relationship between the fulcrum or point of contact between the wire and shoe maintain a fixed relation to the axis of the shoe so that regardless of the wear in 60 use the balance of the shoe on its axis will be maintained uniform.

To accomplish this result we determine the point on the wearing face of the shoe at which this fulcrum should be maintained 65 in order to produce the best results and then at this point cut an aperture through the shoe forming a shoulder with a straight vertical face 15 adjacent to the axis so that as the wearing face wears down the point 70 of the fulcrum will be maintained. This aperture also serves as a means for ready clearance of the wearing face of the shoe from accumulations of dirt, ice, snow, etc., which readily fall through and thus are 75 quickly removed from interfering with the contact and the operation.

The face 15 is further useful in that it provides a convenient means for viewing the shoe to determine the amount of wear. 80 To further facilitate an estimate of the amount of wear we have provided means adjacent the vertical face of said shoulder, here shown as comprising a horizontal pin 17 85 so located that when the trolley wire comes into engagement with the pin it is time to discard the trolley and replace it with a new one. It will be readily understood that various other means might be substituted for the pin and in some instances even a mark on the rear face of the shoulder might serve the purpose though this would be more likely to become obscured by dirt and the like than is the pin 16.

The flanges 13 are continued around at 95 least two sides of the trolley which is roughly circular with flattened parts providing three or four sides approaching the form of

a trapezium. At a side of the trolley adjacent to the face 14 these flanges form a groove with a bottom face 18 along which the wire rides to a wheel 19 during reverse movement of the trolley and the car by which it is carried, as indicated in Figure 2. The wheel 19 and the face 18 are arranged to touch the wire at the same time in backing up, the working faces at 18 and on the 10 wheel being in line with each other.

A narrow bracing portion indicated at 20 connects the part of the trolley adjacent the wheel 19 to the part at the left end of the shoe 14 in Figure 1. This brace 20 is forked 15 adjacent the wheel, the forks corresponding to the flanges 13, and the forks are perforated to provide bosses 21 for the fixed pivot 22 of the wheel 19. In the normal position of the trolley these bosses lie near to 20 but out of contact with the trolley harp but should the trolley get off the wire they can act to limit the swinging movement of the trolley in one direction. Stops 23 are provided at opposite sides of the trolley to 25 limit the movement of the same in the contrary direction, the location of the stops 23 being at the opposite extreme position of the harp from the position where the bosses 21 contact with it.

30 The trolley has a flat fin at 24 through which the pin 12 passes, and copper plates 25 are riveted to said fin by copper rivets 26, said plates being sprung out to bear against the forks 11 of the harp with their 35 outer faces. This construction insures permanent electrical contact of the trolley and the harp, and thus provides for an uninterrupted flow of current.

40 It will be obvious to those skilled in the art that various changes may be made in our device without departing from the spirit of the invention and therefore we do not limit ourselves to what is shown in the drawings and described in the specification, but 45 only as indicated in the appended claims.

Having thus fully described our said invention, what we claim as new and desire to secure by Letters Patent is:

50 1. A trolley shoe having a contact face, one end of the contact face being determined by an aperture in the shoe whereby wear will not affect the relationship between the fulcrum and the axis of the shoe, substantially as set forth.

55 2. A floating trolley having a contact face for a wire, a face intersecting the first-named face to define a fulcrum for the shoe, and a pivot for the trolley so located with relation to the faces as to maintain the balance of the shoe regardless of wear, substantially as set forth.

60 3. A sliding trolley shoe having a contact face for a wire, a second contact face disposed at an angle to the first-named contact face, and a pin between the contiguous ends

of said contact faces for determining the amount of wear on one of said contact faces, substantially as set forth.

65 4. In a trolley structure, a harp having forks, a trolley between the forks having a pair of contact faces with their inner ends in spaced adjoining relation, said contact faces forming an angle the axis of said shoe being disposed in the angle between said contact faces, and copper plates fixed to said shoe and having their outer ends engaging the forks of the harp about the axis of the shoe, substantially as set forth. 75

70 5. A trolley having a contact face for a wire, a pivot for the trolley, and an aperture through the trolley at one end of said face and adjacent to the pivot providing means for permitting the ready clearance of the trolley face through which aperture accumulations may readily pass, substantially 80 as set forth. 85

75 6. A trolley having a shoe for engaging the trolley wire in one direction of movement, a wheel for engaging it on movement in the opposite direction, bosses for the pivot pin of the wheel arranged to engage the harp and limit the movement of the trolley in one direction, and stops adjacent an end of the shoe engaging the harp to limit movement of the trolley in the opposite 95 direction, substantially as set forth.

80 7. A trolley having a shoe normally engaging a trolley wire during forward movement of the trolley, said shoe terminating at its rear end in an abrupt shoulder, a wheel for engagement with said wire on backward movement of the trolley the axis of said wheel being spaced rearwardly from the axis of the trolley during such forward movement, substantially as set forth. 100

85 8. A trolley having a shoe normally engaging a trolley wire said shoe terminating at its rear end in an abrupt shoulder, a wheel spaced rearwardly from said shoulder for engagement with said wire on reverse movement of the trolley, and means in operative relation to said shoulder for indicating the limit of permissible wear on said shoe, substantially as set forth. 105

90 9. A trolley having a shoe normally engaging the trolley wire said shoe terminating at its rear end in an abrupt shoulder, a wheel spaced rearwardly from said shoulder for engagement with said wire on reverse movement of the trolley, flanges on the trolley providing a groove leading from the shoe to the wheel, and a cross bar adjacent said shoulder indicating the limit of permissible wear on the shoe, substantially as set forth. 115

95 10. A trolley having a shoe normally engaging the trolley wire during forward movement of the trolley said shoe terminating at its rear end in an abrupt shoulder, a wheel for engagement with said wire upon 120

125

130

backward movement of the trolley the axis of said wheel being spaced rearwardly from the axis of the trolley during such forward movement, and a face between said shoe and said wheel also engaging the wire upon backward movement of the trolley, substantially as set forth.

In witness whereof, we have hereunto set our hands and seals at Indianapolis, Indiana, this 23rd day of October, A. D. nineteen hundred and twenty-four.
